CLAIM

The ornamental design for a portion of a footwear element, as shown and described.

DESCRIPTION

FIG. 1 is a perspective view of a portion of a footwear element showing our new design;
 FIG. 2 is a side elevational view thereof;
 FIG. 3 is a front view thereof;
 FIG. 4 is a rear view thereof; and,
 FIG. 5 is a top plan view thereof.

The uneven broken line showing the remainder of the shoe is for illustrative purposes only and forms no part of the claimed design.
